COILING STRIP MATERIAL

Albert Richard Norman Heath and Theodore Charles Tapp, London, England

Application April 7, 1941, Serial No. 387,334
In Great Britain April 30, 1940

3 Claims. (Cl. 242—66)

This invention relates to apparatus for coiling or uncoiling metal or other strip material more particularly when the strip is to be passed through some process, for example, an electrolytic plating process, after being uncoiled and before being recoiled. The object of the invention is to provide uncoiling and recoiling apparatus which will be of a simple character and enable the coils of strip material to be readily placed in the uncoiling apparatus whilst, after being recoiled, they can be easily removed. The invention is particularly but not exclusively applicable to an apparatus in which a plurality of coils, not necessarily of the same initial or ultimate diameter, can be treated simultaneously whilst permitting individual coils to be inserted or removed without interfering with the operation of the apparatus.

The uncoiling mechanism may be similar to that by which the strip is recoiled or, if desired, the uncoiling mechanism may differ from the recoiling mechanism not merely by the absence of means for driving the coils but in general design to suit the particular requirements of the operation.

Apparatus for coiling or uncoiling strip material according to the present invention comprises a rotatable support adapted to be engaged by the edge of the coil so as to rotate with the coil and guides on each side of the coil to prevent lateral displacement of the strip. Preferably the apparatus comprises a pair of horizontal shafts having spaced parallel axes, each shaft being provided with rollers and each pair of rollers connected by an endless belt which is sufficiently slack to form a part-cylindrical support for the edge of the coil when the latter is placed on the belt so as to engage the upper surface thereof. When such an apparatus is to be used for recoiling a strip a drive is imparted to the belt through the rollers and their supporting shafts and the peripheral speed of the rollers is greater than the speed at which the strip is fed into the coiling apparatus. Further, the weight of the coil prevents slip between the belt and the coil but slip may occur between the belt and its driving rollers. Hence there is no tendency for the strip to be marked or soiled and any slack in the strip as it is fed to the coiling device is immediately taken up.

When a similar mechanism is used for the uncoiling of the strip no drive is provided since the strip will be drawn off the coil by the pull exerted through the coiling mechanism at the opposite end. Alternatively the belt may be

omitted for the uncoiling mechanism and the coil adapted to rest directly upon suitable rollers mounted on parallel shafts and furnished with vertical guides to prevent lateral displacement of the strip. The path of the strip between the uncoiling and recoiling mechanisms will depend upon the treatment it is to undergo but suitable guide rollers are provided to ensure that the strip is correctly uncoiled and recoiled. The coil may be wound upon a bobbin having one or more radial slots to receive the end of the strip and these bobbins not only form a centering for the coil but supply the necessary weight to prevent slip between the coil and the belt. In some cases a flat spring with a gap between its ends to receive the end of the strip may replace the bobbin.

As the coils do not need a central supporting axle, any individual coil can be introduced or removed from the uncoiling or recoiling apparatus independently of those on either side of it and adjacent coils can be of widely different diameters without necessitating any change in the design of the apparatus.

Two constructions of apparatus according to the present invention are shown by way of example in the accompanying drawing, in which

Figure 1 is a side elevation showing substantially similar uncoiling and recoiling mechanisms,

Figure 2 is a plan,

Figure 3 is a detail on an enlarged scale showing a bobbin in side elevation,

Figure 4 is a similar view of the coil prior to uncoiling,

Figure 5 shows in side elevation on an enlarged scale an alternative form of uncoiling mechanism,

Figure 6 is a plan of Figure 5, and

Figure 7 is a detail showing the guide rollers and vertical spacing bars incorporated in the construction shown in Figures 5 and 6.

The strips of sheet material are usually initially in the form of coils wound upon a circular spring 1 (Figure 4) and prevented from unwinding by means of a retaining band 2. The end of the strip A may be introduced into the gap 1a between the two ends of the circular spring 1. Each coil may be of relatively large diameter when fully wound and a considerable number of these strips, for example twenty-four, can be dealt with simultaneously in the uncoiling and recoiling apparatus. In the example illustrated it is assumed that steel strips are to be unwound and pass through a bath for plating

them with zinc by an electrolytic process before they are recoiled but the particular process to which the strips are subjected forms no part of the present invention.

The uncoiling mechanism comprises a bed 3 in which are mounted to rotate two horizontal shafts 4 spaced apart and each provided with a number, for example twenty-four, of rollers or pulleys 5 having lateral guide discs or flanges 6, the flanges being slightly more widely spaced than the width of the strip A. The rollers 5 may be eight inches in diameter and the discs 6 may be about sixteen inches in diameter. Connecting each pair of pulleys is a slack belt 7 adapted to form an arcuate bearing member for the edge of the coil when the latter is placed in position so as to engage the upper surface of the belt. The weight of the coil is taken wholly by the rollers and the belt serves merely to prevent marking of the strip. As the strip A is uncoiled, the diameter of the coil bearing upon the belt is reduced but any slip which occurs takes place between the belt 7 and the rollers 5 and not between the strip A which has a relatively rough surface and the belt. The strip is led upwards over a guide pulley, diagrammatically shown at 8, before passing through the plating or other tanks generally indicated at B. As clearly shown in Figure 1 the uncoiling apparatus can simultaneously support coils of very different diameter, for example a coil which is fully wound and one which is almost completely unwound, the fully wound coil being shown in broken lines and the small diameter coil at A¹ by a full line.

After passing through the tank B the strip A passes over a guide roller 8a to the recoiling apparatus. This is very similar to the uncoiling apparatus already described and comprises two parallel shafts 4a, 4b each carrying pulleys 5a with deep flanges 6a. Each pair of pulleys is connected by a slack belt 1a adapted to form a part-cylindrical support for the bobbin 9 prior to the strip being wound upon the latter. The bobbin is provided with a series of slots 9a into which the end of a strip can be introduced and the amount of slack in each belt 1a is such that the bobbin or coil rests upon its surface and is supported by the belt in spite of changes in the diameter of the coil. Thus the empty bobbin 9 is shown by a full line and the fully wound coil by broken lines at 10 in Figure 1. The shafts 4a, 4b are driven from a motor 11 through a chain 12 and sprocket 13 on one end of the shaft 4a and a chain 14 connects the opposite ends of the shafts. By this means the belts 1a are caused to rotate and when a coil or bobbin rests upon them, the bobbin is simultaneously rotated so as to wind the strip upon it, until the strip A is fully wound on the bobbin, whereupon the bobbin with its coil of strip material can be removed and replaced.

The speed at which the parallel shafts 4a, 4b are rotated is such that slip must occur either between the pulleys 5a and the belts 1a or between the belts and the surface of the strip A, and the arrangement is such that in practice

slip will occur between the pulleys and the belts rather than between the belts and the strip A, so that any damage or scratching of the strip after it has been plated is avoided.

5 Instead of using an uncoiling arrangement as shown in Figure 1, i. e. instead of using a device which only differs from the recoiling apparatus in the omission of driving means for the pulleys and belts, the alternative construction shown in 10 Figures 5 to 7 may be employed. This arrangement comprises a framework 15 supporting two parallel shafts 16 spaced apart and each carrying a series of rollers 13 provided with flanges 17. The rollers may be supported on ball bearings 18 so as to rotate freely. The distance between the flanges enables each roller to receive a coil of strip material and vertical spacing bars 19 are provided supporting at their upper ends guide pulleys 20, additional guide pulleys 21 being also mounted at the rear of the frame.

15 The shafts 16 are so spaced that the rollers they carry will support a coil in its fully coiled state and also up to the point where it is fully uncoiled, i. e. until only the flat spring 1 remains. 20 The vertical spacing bars 19 act as additional means for preventing lateral displacement or tilting of the coils and the base of the framework is conveniently inclined as shown so as to facilitate the loading on of the coils.

25 It is to be understood that the constructions above described are given by way of example only and that details may be varied without departing from the invention.

30 What we claim as our invention and desire to secure by Letters Patent is:

35 1. Apparatus for coiling a plurality of coils of strip material comprising a pair of horizontal shafts having spaced parallel axes, rollers mounted on said shafts, a slack endless belt connecting each pair of rollers and adapted to form an arcuate bearing member for the edge of each coil which bears upon the upper surface of said belt, guide flanges on either side of each roller to prevent lateral displacement of the coils, and 40 means for driving the shafts so as to impart rotation to the coils.

45 2. Apparatus for coiling strip material as claimed in claim 1 in which the peripheral speed of the rollers is greater than the speed at which the strip is fed into the coiling apparatus whereby slip can occur between the belt and rollers but not between the belt and the coil.

50 3. Apparatus for coiling a plurality of coils of strip material comprising a pair of horizontal shafts having spaced parallel axes, a plurality of rollers mounted on said shafts, lateral guide members between each roller, a slack endless belt connecting each pair of rollers and adapted to form an arcuate support for the edge of the 55 coil of strip material which rests upon it, and means for driving the belt and the coil it supports so that the peripheral speed of the belt is greater than the speed at which the strip is fed into the apparatus.
